United States Patent Office.

JAMES TWAMLEY, OF NEW YORK, N. Y.

Letters Patent No. 104,229, dated June 14, 1870.

IMPROVED TAG FOR SHOE-STRINGS.

The Schedule referred to in these Letters Patent and making part of the same.

To all whom it may concern:

Be it known that I, JAMES TWAMLEY, of New York, of New York county, in the State of New York, have invented a certain new and useful improvement in Shoe-Tags; and I do hereby declare that the following is a full and exact description thereof, reference being had to the accompanying drawing making part of this application.

My invention relates to a new method of securing the metallic tag to the cord of sleeve, corset, or other lacing.

Previous to my invention it has been customary to effect the retention of the metal tag (or tube) on the cord by making one or more indentations in the tube, which would tend to prevent the said tag or metallic tip from slipping off of the cord, or to make one or more slight perforations in the metal, so that the bur formed by punching said holes (as well as the indentations) would hold the tube fast onto the cord. But it has been found in practice that these methods do not induce to such a permanent securing of the metallic tube to the cord as is desirable, and it is well known that, in common use, a very large proportion, if not a majority, of the metallic tips peel off after a short use of the lacings, especially in the use of shoe-lacings.

My invention has for its object to provide a simple and economic means for effectually securing or fastening the metallic tubes or tip on the ends of shoe, corset, and other lacings or cords, and consists in cutting one or more barbs or spear-shaped points in the metal tube and bending said barb or barbs into the confined end of the cord or lacing in such a manner as to gripe the cord, and so that any strain on the cord which would tend to pull it out of the tube will induce to a greater hold of the barbs on the cord, as will be hereinafter more fully explained.

To enable those skilled in the art to make and use my invention, I will proceed to describe it more fully, referring by letters to the accompanying drawing, in which—

Figure 1 is an elevation of part of a common shoe-lacing having the metallic tip or tag attached to it, according to my invention;

Figure 2 is a view showing the tube unrolled or straightened out, to more clearly illustrate the shape

and arrangement of the gripping-points or barbs which gripe the cord; and

Figure 3 is a longitudinal section through the cord and tag.

In the several figures—

A is the cord or lacing, such as commonly used, and B is the metallic tip or tag.

This tube B is made and applied to the cord in the usual manner, except that, in lieu of having one or more simple (round) holes or indentations, it has one or more barbs or points, 1, 2, 3, formed in it, as clearly shown, which points are bent inward, as seen at figs. 1 and 3, so as to impinge upon and penetrate partially the stock or material of the cord A.

It will be seen that when the barbs 1, 2, 3 are bent into the cord A, as shown at fig. 3, they not only will gripe and hold the cord in the tube, but that any pull on the cord (in the direction indicated by the arrow at fig. 3) will tend to make said barbs or points bend further in, and buckle or cramp into the cord so as to render the extrication of the latter wholly impossible. It will be understood that the barbs or points 1, 2, 3 can be cut and struck in by the same mode of operation, and with the same facility, as that with which the manufacture of shoe-tags, as now made, is conducted, and it will also be understood that the number, size, and arrangement of the barbs may be varied at pleasure, without departing from the spirit of my invention. In lieu of having the barbs all in line, as shown, they may be distributed around the surface of the tube A.

Having described my invention so that those skilled can make and use it,

What I claim as new, and desire to secure by Letters Patent, is—

A shoe-tag, or tip, provided with one or more barbed securing-points, substantially in the manner and for the purpose set forth.

In testimony whereof I have hereunto set my hand and seal, this 5th day of April, 1870.

JAMES TWAMLEY. [L. S.]
